CLICKER DIE STOCK

Carl G. Deubel, Shiremanstown, Pa., assignor to
Progressive Service Company, St. Louis, Mo., a
corporation of Missouri

Application February 1, 1937, Serial No. 123,355

3 Claims. (Cl. 76—107)

This invention relates to clicker die stock.

An object of the invention is to provide an improved clicker die stock for use in making clicker dies; said stock comprising a cold drawn 5 steel strip having the essential qualities and characteristics, with the exception of the qualities and characteristics created and imparted by the methods and processes hereinafter described, for forming the improved completed clicker die; 10 said stock being essentially preshaped with a substantially flat intermediate side portion and with two short outwardly inclined bevels at the edges of said stock and at the inside of the die when the die is formed, and with an outer surface 15 which is substantially symmetrically arcuate in cross-section from the lower edge to the upper edge of the stock; so that, after the die stock is formed in the shape of a clicker die, determined by a pattern used by the maker, and after the 20 ends of the stock have been welded together while the stock is on or about the pattern, the die may be ground or otherwise treated to remove the high or protruding portions at its welded ends and ground down or processed to the 25 same height as the original die stock, after which the die is hardened and tempered and then straightened and sharpened to knife edges by grinding on a wheel or the like, or otherwise treating, the inner and outer edges of the bevelled and curved surfaces, respectively, and, there- 30 after, the edges are resharpened to extremely sharp edges by hand operation or other means. The die may be painted in any selected color.

By use of my improved die stock, the operation of forming the die with opposed sharp cutting edges is greatly facilitated and the time required to make the die is minimized to such an extent that a die with double sharp cutting edges may be made and finished in approximately the 40 same time required to make a die with a single cutting edge according to present practice.

In making clicker dies in accordance with this invention, I use cold drawn steel stock having a width of exactly or approximately nine-sixteenths of an inch, so that the thickness of the die in proportion to its height is considerably greater than any clicker dies with which I am familiar, thus providing a much stronger clicker die than can be made by use of die stock having 45 a greater width in proportion to its horizontal thickness. Therefore, an additional object of the invention is to provide a clicker die made of cold drawn steel that is stronger than the usual clicker dies at present in use. It is immaterial 50 whether carbon or alloy steels are used.

Other objects of the invention should be readily apparent from the following description, considering that the invention applies to cold drawn steel of all of the shapes within the disclosure and only one of which is illustrated in the annexed drawing, and bearing in mind that I contemplate the use of cold drawn steel die stock as an essential part of the invention, and reference being made to the annexed drawing, in which—

Fig. 1 is a perspective view of a section of my improved preshaped die stock enlarged somewhat beyond the proportions required for making a double edged clicker die having a height of approximately nine-sixteenths of an inch.

Fig. 2 is a perspective view of a die formed from the preshaped die stock after the die has been sharpened and straightened after hardening and tempering.

Fig. 3 is a sectional view on the line 3—3 of Fig. 2 after the die has been hardened, sharpened and straightened.

The cold drawn steel stock is preshaped approximately as shown in Fig. 1, and is furnished by the manufacturer of the stock in a cold drawn steel strip having a width preferably nine-sixteenths of an inch, or any width as desired, and provided with a symmetrically curved outer surface 1, with a flat intermediate inner surface 2 and with marginal outwardly inclined bevels 3 and 4 intersecting the upper edge 5 and the lower edge 6 of the stock, respectively. I have obtained this preformed cold drawn steel stock in this satisfactory form and at permissible cost and finished and held to a very close tolerance with respect to the edges 5 and 6 and also with respect to the thickness of the stock, including the curved outer wall 1, the flat intermediate wall 2, and the relatively narrow bevels 3 and 4. Such a strip of cold drawn steel, when preshaped in this manner, requires only bending about a pattern to form the die, welding the abutting ends 7, then grinding or filing down the high portions of the weld so as to conform to the approximate height and thickness of the original die stock, including the thickness of the edges 5 and 6.

Next, the die is hardened and tempered and then straightened by grinding or otherwise treating its opposite edges. Next, both edges are sharpened to knife edges on a wheel or the like, one edge being ground approximately on the angular lines 8 and 9 and the opposite edge on the lines 10 and 11. After being thus treated and sharpened to a knife edge, both edges 12 and 13

are resharpened by a manual operation to extremely sharp edges so that they will readily cut through the leather or material to be died out by this improved die.

5 Obviously, this die is reversible so that, after one edge has been used, the die may be reversed and the opposite edge used. Thus, this die may be used to cut or form opposed duplicate parts of a shoe upper or the like and, therefore, serves the triple function of cutting duplicate forms, of being reversible to use both edges in cutting matching or cooperating parts of a shoe upper or the like, and of double durability.

10 My improved die stock may be made of cold drawn carbon steel or an alloy steel of appropriate sizes and shapes. The preferred size and shape is a stock that is about nine-sixteenths of an inch in width or height, and having a tolerance range between .032" to .0" at the edges.

15 20 This is to say that the preferred stock must have a width essentially about nine-sixteenths of an inch before the edges are treated to form the sharp cutting edges of the die. The tolerance indicated is enough to allow for the sharpening 25 of both edges of the die after the die has been shaped from the stock having a width of about nine-sixteenths of an inch with allowance for sharpening.

25 30 This improved die stock has dimensions affording the needed tolerance range for treatment to form the two opposite sharp cutting edges after the die has been shaped without substantially reducing the width or height of the die. In its original form, as shown in Fig. 1, the opposite 35 edges of the die stock are nearly uniform and both edges can be sharpened by removing approximately the same amount of material from the two edges. Being reversible and having the 40 two opposed edges, the same die can be used to cut or form the two side portions of a shoe upper, one side of the die being used to form one side portion and the opposite side of the die being used to form the opposite side portion of the shoe 45 upper.

45 50 This invention is an advance and improvement over the invention disclosed in my prior Patent No. 2,049,157, July 28, 1936, and has been found to be, and has been accepted as, an advantageous advance in the art thereover because, by use of this new die made from this improved die stock, by this method and process, a die

having the foregoing and other advantages over said patented die is made.

5 The bending of the stock to form the die may be effected by heating the die stock only at the points being bent and very quickly in order not to change the quality or character or temper to any undesired extent, as disclosed in my said prior patent.

10 15 By this invention I obtain all of the advantages and savings disclosed in my said prior patent, in addition to the advantages and savings herein disclosed and suggested, or otherwise now apparent from this disclosure. The invention has been found to meet an existing need in these particulars and, without restricting myself in any unessential particulars, what I claim and desire to secure by Letters Patent is:—

15 20 25 1. Clicker die stock comprising a cold drawn steel strip having upper and lower edges of perceptible width, a symmetrically arcuate outer wall, and an inner wall having beveled opposite marginal portions, said arcuate outer wall and said beveled marginal portions intersecting said upper and lower edges, the die stock being substantially of finished clicker die cross sectional dimensions and of gradually increasing thickness from each of said edges to its longitudinal horizontal center.

30 35 40 2. Clicker die stock comprising a cold drawn steel strip having upper and lower edges of perceptible width, a symmetrically arcuate outer wall, and a substantially vertical inner wall having beveled opposite marginal portions, said arcuate outer wall and said beveled marginal portions intersecting said upper and lower edges, the die stock being substantially of finished clicker die cross sectional dimensions and of gradually increasing thickness from each of said edges to its longitudinal horizontal center.

45 50 55 3. Clicker die stock comprising a cold drawn steel strip approximately nine-sixteenths of an inch in height and having upper and lower edges of perceptible width, a symmetrically arcuate outer wall, and an inner wall having beveled opposite marginal portions, said arcuate outer wall and said beveled marginal portions intersecting said upper and lower edges, the die stock being substantially of finished clicker die cross sectional dimensions and of gradually increasing thickness from each of said edges to its longitudinal horizontal center.
